UNITED STATES PATENT OFFICE

CHARLES M. NORTON, OF GRAND RAPIDS, MICHIGAN

DOOR LATCH

Application filed March 18, 1929. Serial No. 347,765.

This invention relates to a door latch which is of particular utility when used in conjunction with garage doors. The latch is capable of use with a garage or any other type of door 5 and may be operated at a distance from the door to unlatch the same, or the door may be disengaged from the latch directly at the door itself.

The invention resides in many novel constructions and arrangements of parts for effectively producing a simple, practical and serviceable latch of the character noted, understanding of which may be had fully from the following description taken in connection 15 with the accompanying drawings, in which,

Fig. 1 is a fragmentary vertical section through a door and the adjacent upper portion of the door casing having the latch construction of my invention applied thereto, 20 and with the door mounted to swing inwardly.

Fig. 2 is a like section illustrating the latch mechanism used on the door, the door being mounted to swing outwardly.

Fig. 3 is a fragmentary section similar to that shown in Fig. 2, showing the manner in which the latch parts may be disengaged from a distance, and

Fig. 4 is a somewhat enlarged perspective 30 view of one of the elements of the latch structure.

Like reference characters refer to like parts in the different figures of the drawings.

The door 1 may be of any usual construction mounted for swinging movement about a vertical axis at one edge of the door and in which the upper end portion of the door engages against a stop 2 when door is in closed position. In Fig. 1 a stop 2 is positioned 35 with reference to the door so that the door may swing inwardly but not outwardly and in Fig. 2 this position is reversed.

The door stop 2 is secured underneath an upper bar 3 which is at the upper side of the door opening which opening is made in the garage wall 4 in the usual manner.

In the construction shown in Fig. 1, two vertical latching rods 5 are mounted for slide- 45 able movement at the inner side of the door in upper guides 6 and lower sleeves 7 which have

a slot in one side thereof, the rods being turned outwardly at right angles, as indicated at 8, and extending through slots in the door to the outer side thereof. A coiled spring 9 within the sleeve 7, which has a 55 closed lower end, normally serves to lift each rod 5 to an upper position. But by engaging with the end of the handle 8 and pressing downwardly thereon the rod may be moved to a lower position as is evident.

In Fig. 2 where the door is mounted to swing outwardly the rods 5 are mounted in the same manner but on the outer side of the door and the handles 8 are shorter and extend outwardly through slots in the sleeves 7. 60 They likewise are operable at the outside of the door.

A cooperating latching element is mounted at the underside of the bar 3 extending away from the stop 2 over the upper edge of 70 the door 1. In the form shown in Fig. 2, where the door swings outwardly, the latch element consisting of plate 10 and an upwardly extending bar 11 integral therewith, is permanently secured to the underside of the bar 75 3, said bar 11 passing upwardly at the outer side of the building; while in the structure shown in Fig. 1 the bar 11 is turned upwardly at the inner side of the building and at its upper end is provided with an arm 11a as 80 shown.

At the lower side of the plate 10 detents 12, preferably of spring material, are permanently secured at one end, extending outwardly 85 at their free ends beyond the bar 3 and near their free ends having openings through which the rods 5 may pass. The free ends of the detents 12 are curved upwardly.

A wire or cable 13 is attached to the free end of each detent 12 extending upwardly 90 therefrom and the two wires converge and connect together and to the lower end of a third wire or cable 14 which is secured to the upper end of the bar 11 in the construction shown in Fig. 2 or to the end of the arm 11a 95 in the construction shown in Fig. 1. A wire or cable 15 is connected to the several wires 13 and 14 at their juncture and extends outwardly and away from the building or garage. This necessitates, in the structure 100

shown in Fig. 1, that the wire 15 shall be passed through suitable openings in the building wall 4.

With either construction it is evident that 5 the door may be unlatched from the detents 12 by engaging the ends 8 of the latch rods 5 moving them downwardly. When this is done the door is free to be swung about its 10 hinged mountings. This is very desirable in opening the door when one is close thereto.

To unlatch a door at a distance the wire 15 is pulled at any distance from the door to which it may be led whereupon the detents 12 are lifted, as indicated in Fig. 3, disengaging the same from the upper ends of the rods 5. The door in such cases is disengaged and free for movement and usually in such a case the door is operated by weights or springs so as to open freely as soon as the 20 latching disengagement has been effected. It is evident that on closing the doors, the upper ends of the rods pass under the upturned curved free ends of the detents 12 until the openings through said detents are 25 reached whereupon the upper end portions of the rods are received in the openings and latch the doors in closed position.

The bar 11 in either of the structures is 30 preferably provided with an opening 11b directly opposite the point where the wire 15 joins the flexible cables 13 and 14 so that the wire 15 may be extended in the opposite direction through the opening 11b as indicated at 15a in Fig. 1. By this means the 35 wire 15 may be extended in either direction in either of the structures for operation from either inside or outside of the building as desired. This is feasible because it makes no difference which direction the cables 40 13 and 14 are flexed from straight line position to lift the detents 12.

This construction of door latching device is 45 simple and easy to manufacture and is quickly and readily installed. It is, as fully set forth in the previous description, applicable and useful irrespective of the direction in which the doors swing. Variations in the details of construction may be resorted to without departing from my invention which 50 is defined in the appended claims and is to be considered comprehensive of all forms of structure coming within the scope of said claims.

I claim:

55 1. In combination, a door, a door frame around the door, a vertical rod mounted on the door, a spring member attached at one end to the door frame over said door and extending over said rod and having means 60 with which said rod engages, a cable attached at one end to the free end of the spring member and at its opposite end having a permanent connection, and a second cable secured to the first cable between its ends and extending 65 65 away therefrom at substantially a right

angle, whereby on pulling on said second cable the spring member may be lifted to disengage from said rod.

2. In a construction of the class described, 70 a door, a door frame around the door, two rods mounted on the door having ends thereof extending beyond an edge of the door, a plate secured to the door frame and provided with a bar at one side extending at right angles to said plate and away from the door, two 75 spring members secured at one end to a side of the plate and extending across the ends of said rods, and provided with means to engage with said rods, cables attached one to the free end of each of the spring members, said cables converging and joining together, a second cable attached to said bar at their converging ends, and a third cable connected to all of said cables at the juncture thereof, 80 adapted to extend outwardly in a horizontal 85 direction for the purposes described.

3. In a latching device of the character described, a plate of flat metal having a bar bent therefrom at right angles at one edge, a 90 spring member secured at one end to one side of the plate and having a free end portion extending beyond the edge of the plate to which said bar is located, said spring member being provided with means to effect latching engagement thereof with a rod or bolt, 95 a cable connecting the free end of said member and said bar, and a second cable connected to the first cable between its ends extending therefrom to a distance whereby the spring member may be drawn toward the said 100 base on pulling on the second cable.

4. In combination with a door and door casing, 105 a latch bolt on said door, a yieldable keeper on said door casing, interengageable means on said keeper and latch bolt, a flexible member extending substantially in alignment with the direction of movement of said keeper, said flexible member being attached at one end to said keeper and having its opposite end fixed relative to the casing and means connected to said flexible member between its 110 ends extending away therefrom at substantially right angles and operable to flex said member out of straight line position whereby the keeper is moved away from said bolt.

5. In combination with a door and door frame, 115 a latch bolt mounted on the door, a plate mounted on the door frame, a spring keeper fixed at one end to said plate and having its other end movable relative to the plate, 120 interengaging means on the keeper and latch bolt, an arm extending rigidly from said plate, a flexible member extending substantially in alignment with the movement of the free end of the spring keeper, said flexible member being attached at one end to the free end of said keeper and at its opposite end to said arm, the middle portion of said flexible member being normally spaced from said arm and operating means connected to said flex- 125 130

ible member between its ends for flexing said flexible member out of straight line position, said flexible member being operable when flexed in any direction lateral to its longitude.

6. In a device of the class described, a plate, two spring keepers, each fixed at one end to said plate and each having a movable free end, an arm on said plate, two flexible members, one for each spring keeper, each flexible member extending substantially in alignment with the movement of the free end of the keeper and each having one end attached to the free end of the keeper, the opposite ends of the flexible members being joined, a continuation flexible member attached to the joined ends of the two flexible members and having its opposite end attached to said arm and means connected to said flexible members between the fixedly connected end and the ends attached to the keepers for flexing said members out of straight line position.

In testimony whereof I affix my signature.
CHARLES M. NORTON.
